(57) **CLAIM**

The ornamental design for a back to back connector for a power transmission and communications system as shown and described.

DESCRIPTION

FIG. 1 is a rear view of a back to back connector for a power transmission and communications system showing our new design.

FIG. 2 is a rear perspective view thereof;

FIG. 3 is a front view thereof;

FIG. 4 is a front perspective view thereof;

FIG. 5 is a top view thereof;

FIG. 6 is a right side view thereof;

FIG. 7 is a left side view thereof; and,

FIG. 8 is a bottom view thereof.
